BOTTLE CAP

David L. Lundberg, 3417 S. 77th St.,
Omaha, Nebr. 68124

Filed Mar. 24, 1969, Ser. No. 16,412

Term of patent 14 years

Int. Cl. D9—02

U.S. Cl. D9—275

FIG. 1

FIG. 2

FIG. 4

FIG. 5

FIG. 6

Des. 221,421

PAGE 2

FIG. 3

FIG. 7

FIG. 8

FIG. 9

FIG. 1 is a perspective view of the bottle cap showing my new design;

FIG. 2 is a top plan view thereof with the closure in an open position;

FIG. 3 is a side elevational view thereof with the opposite side being a mirror image thereof;

FIG. 4 is a bottom plan view with the closure in a partially open position;

FIG. 5 is a top plan view of a modified embodiment of the bottle cap with the closure thereof in an open position;

FIG. 6 is a top plan view of the modified embodiment with the closure in a closed position;

FIG. 7 is a rear elevational view of the bottle cap as shown in FIG. 1;

FIG. 8 is a perspective view of the modified embodiment; and

FIG. 9 is a bottom plan view of the modified embodiment.

I claim:

The ornamental design for a bottle cap, substantially as shown and described.
